H. SCHMIDT,
WINDOW,
APPLICATION FILED SEPT. 13, 1920.

1,437,449.

Fig. 1 Fig. 2

UNITED STATES PATENT OFFICE.

HANS SCHMIDT, OF OEJENDORF, NEAR HAMBURG, GERMANY.

WINDOW.

Application filed September 13, 1920. Serial No. 410,064.

To all whom it may concern:

Be it known that I, HANS SCHMIDT, a subject of the German Republic, and resident of Oejendorf, bei Hamburg, Germany, have invented certain new and useful Improvements in Windows (for which patents have been obtained in Germany, No. 299,999, dated April 29, 1914; No. 306,669, dated December 24, 1914, and No. 323,694, dated February 27, 1919; in France, No. 518,630, dated June 28, 1919; in Belgium, No. 282,519, dated September 30, 1919; and an application filed in Holland April 22, 1920), of which the following is a specification.

This invention relates to a window comprising two sashes arranged to lie in the same plane when closed, the top sash being guided by pins movable in grooves in the window frames, whilst the bottom sash is adapted to swing with respect to the frame. The bottom sash is mounted on swinging arms hinged to the window frame, by means of which arms it can be swung on its horizontal axis, whilst the top sash is adapted to slide in the window frame, and is drawn downward when the bottom sash is tilted, and can then also be tilted about a horizontal axis. In this way the outsides of the two sashes of the window are turned inward, so that they can be easily cleaned from inside the room.

The subject of the invention is illustrated in the accompanying drawing, which shows two preferred forms of the invention.

Figures 1 and 2 are vertical sections of the first form of the window with closed and opened sashes respectively shown; Fig. 3 is a vertical section of a modified form showing the upper sash open; Fig. 4 is a vertical section of the form shown in Fig. 3 with the parts in closed position; Fig. 5 is section on line 5—5 Fig. 4.

The window consists of the top sash *b* and the bottom sash *c* which are mounted in the frame *a*. The top sash is guided between the grooves *d* of the window frame by means of pins *e* and *f*. The bottom sash is connected to the top sash by means of a hinge *g* at the butt joint, and is pivotally connected by pins *l* to rods *h* which are hinged to the window frame at *i*. The window frame is provided with a groove *k* in which a corresponding fillet *c'* of the sash fits in order to make a tight joint.

When the top sash *b* is pulled down, the bottom sash *c* describes a tilting movement

about the pins *l*. If the bottom sash be tilted further, the top sash slides down simultaneously, and then can also be tilted about its horizontal axis, in consequence of the guide pins *f* passing out through gaps *d'* in the window frame.

In the modified form shown in Figs. 3 to 5 the top sash *b* is connected to bottom sash *c* by means of a link *m* on each side of the sash. The upper end of each link is pivotally connected by a pin *m'* to the top sash above the lower rail and the lower end of each link is formed with an angular projection or arm *m''* which is pivotally connected to the lower sash by a pin *m'''*. Guide pins *m''* on the links project into the longitudinal grooves *d* formed in the frame. A two-arm lever *n* is arranged on the window frame, and its longer arm carries a pin *n'*, which is bent at a right angle and adapted to be received behind an arm *o* attached to the top sash *b*. A rod *p* operated by a handle *r*, is pivoted on the short arm of the lever *n*.

The window can be locked by turn buttons *s* (Fig. 5) of known construction provided on the bottom sash as well as on the top one.

This form of window has the advantage that the top sash can be kept open while the lower sash is closed. To open the top sash, the turn buttons are rotated to release both sash. The handle of the lever *r* is pressed upward causing the free end of lever *n* to press against the upper sash. Simultaneously with the pressure on the lever, the lower end of the bottom sash is manually pushed out and when the upper and lower sash (matched rails) become separated the upper sash is opened and the lower sash can be again closed. To close the upper sash when the lower sash is closed the latter must first be pushed out; the handle of lever *r* is then depressed causing the pin *n'* to engage the arm *o* and swing the upper sash inward into the position shown in Fig. 4, the lower sash is then pulled in and locked by the turn-buttons *s*.

What I claim is:

1. The combination with a window frame having grooves of two sashes arranged to lie in the same plane and pivotally connected together, pins near the upper end of the upper sash arranged to slide in said grooves from the top to the bottom thereof, and a suspending rod piv-

oted at one end to the lower sash and at the other end to said frame and means including said rod whereby said sashes may be reversed when said pins reach the bottom of 5 said groove and the lower sash is wholly displaced from the frame.

2. The combination with a window frame having grooves from top to bottom; of two sashes normally arranged in the 10 same plane and hinged together; means to movably suspend the lower sash only from the frame and means for holding the upper sash open outwardly while the lower sash is fully closed.

15 3. The combination with a window frame having an upper and a lower sash, pivotally connected together of means to permit the lower sash to swing outwardly while the upper sash slides to the bottom of said 20 frame, and means for holding the upper sash outwardly inclined while the lower sash is fully closed.

4. The combination of a window frame, an upper sash adapted to slide in the plane 25 of the frame from the top to the bottom thereof, a lower sash, means for flexibly connecting the sashes together, means whereby the lower end of the upper sash may be swung free of the frame, and means 30 whereby the normal position of the lower sash may be substantially reversed.

5. The combination of a window frame, two sashes adapted to lie therein in the same plane, means flexibly connecting the sashes 35 together the top sash adapted to slide in

the plane of the frame from the top to the bottom thereof, laterally extending gaps formed in the frame whereby the lower end of the upper sash may be swung free of the frame, and supports pivoted near the top 40 of the frame and directly pivoted to the lower sash adapted to permit the normal position of the latter to be substantially reversed.

6. The combination with a window 45 frame having an upper and a lower sash hinged together, and means for movably suspending the lower sash from the frame, of means to permit the upper sash to move to the bottom of said frame when the lower 50 sash is pushed outwardly and means to permit the lower end of the upper sash to also swing outwardly and to hold the lower sash outwardly swung.

7. The combination with a window 55 frame having an upper and a lower sash hinged together, and means for movably suspending the lower sash from said frame, of means to permit the upper sash to move to the bottom of said frame when the lower 60 sash is pushed outwardly and means to permit the lower end of the upper sash to also swing outwardly to hold the lower sash outwardly swung, and mechanism to prevent at will the complete lowering of the 65 upper sash and to hold it outwardly swung while the lower sash is fully closed.

Signed by me at Hamburg, this second day of July 1920.

HANS SCHMIDT
